WINDOW SASH

Valentine L. Thoma, Pittsburgh, Pa.

Application February 14, 1934, Serial No. 711,174

2 Claims. (Cl. 20—56.4)

My invention relates to window sash construction and the like, and more particularly to a metallic sash frame consisting of rails or strips which are detachably connected together to permit of convenient installation or removal of window panes. It will be understood that the invention is also applicable to show cases, etc.

One object of my invention is to provide a metallic sash structure composed of separable parts which can be readily assembled and disassembled, and wherein there are no exposed bolts or screws.

Another object of my invention is to provide in a sash structure, clamping members or bars, together with means for bringing the members into gripping engagement with the sides of a glass plate, without danger of exerting excessive clamping pressure on the plate.

Still another object of my invention is to provide a metallic sash structure of generally simplified and improved form.

As shown in the accompanying drawing, Figure 1 is an elevational view partly in section, looking from the outer side of a window installation; Fig. 2 is a view taken on the line II—II of Fig. 1; Fig. 3 is a view taken on the line III—III of Fig. 1, and Fig. 4 is a sectional plan view of the structure of Fig. 1, with a portion of the glass broken away.

For convenience of illustration and description, I have shown the structure as applied to a wooden window sill 5, which has the usual base board 6. Only the lower sash bar is shown, it being understood that the sides and top of the sash may be formed in the same manner or in any other suitable manner. The sash bar is composed of a sash rail 7 and a retaining strip 8, which may be formed of yieldable metal strips, extruded metal, or other suitable material.

The rail 7 has a base portion 9, a wing 10, and a channel or trough portion 11. The retaining strip 8 has a wing 12, and a glass-engaging shoulder 13. The glass plate or pane 14 is shown as held between the channel 11 and the shoulder 13. A projecting strip 15 of sheet metal or the like is shown as overlying the outer edges of the board 6.

The sash rail 7 is secured to the board 6 by a suitable number of screws 16, and a seat block 17 is provided at each end of the sash, for taking the vertical weight of the glass 14. As here shown, the blocks 17 are of tubular form, with cushioning material 18, such as rubber or felt on their upper sides. The ends of the wings 10 and 12 are cut away somewhat as shown more

clearly in Fig. 4, to permit the placing of the seat blocks 17.

The wing 10 is tapped for the reception of screws 20 which extend into open-ended slots at the inner edge of the wing 12. When the screws 20 are set in position, they serve to secure the sash rail 7 and the retaining strip 8 together.

In assembling the parts, the glass is placed upon the blocks 17, whereupon the retaining strip 8 is moved inwardly to cause the glass to be firmly, but yieldably gripped between the shoulder 13 and the channel 11, whereupon the screws 20 are driven home to firmly clamp the wings 10 and 12 together. The thickening of the wing 12 toward its free edge, insures that the retaining strip 8 will not accidentally slide outward away from the face of the glass, because it has wedging engagement with the head of the screw 20.

Suitable holes 22 (Fig. 2), are provided in the channel 11 to permit of access with a screw driver to the heads of the screws 20. The channel 11, of course, catches condensed moisture and melted ice or frost at the inside of the window, and prevents such moisture or water from flowing to the window sill 5. The moisture will drain down through the sash past the lower edge of the retaining strip 8 which is vertically-spaced from the base rail 9, and finds its way over the ledge 15 at the outside of the building.

From the foregoing, it will be seen that the glass is not subjected to strains through tightening of the screws 20, thus reducing danger of breaking the glass, and that both the screws 20 and the screws 16 are concealed, and therefore do not detract from the appearance of the structure, and are protected from the weather.

I claim as my invention:—

1. A sash structure comprising a sash rail having a base portion adapted to be secured to a frame and a rail portion extending upwardly from the base and offset inwardly at its upper edge, for engagement with one side of a pane, a wing carried by the rail portion in vertically-spaced relation to the base, a retaining strip for engaging the opposite side of the pane and having a wing in horizontally-overlapping relation to the first-named wing, and means for adjustably connecting the said wings, the said retaining strip being supported by said wings, with its lower edge vertically spaced from the upper surface of said base portion.

2. A sash structure comprising a sash rail hav-

ing a base portion adapted to be secured to a frame and a rail portion extending upwardly from the base and offset inwardly at its upper edge, for engagement with one side of a pane, 5 a wing carried by the rail portion in vertically-spaced relation to the base, a retaining strip for engaging the opposite side of the pane and having a wing in horizontally-overlapping rela-
tion to the first-named wing, and means for adjustably connecting the said wings, the said retaining strip being supported by said wings, with its lower edge vertically spaced from the upper surface of said base portion, the said base portion being extended outwardly past the outer side of said retaining strip. 80
